Geo. Bruce, of New York, N.Y.
Letters Patent No. 1014 - Dated June 15, 1858.

The schedule referred to in these Letters Patent & making part of the same.

To all whom it may concern:

Be it known that I, George Bruce of the City & County of New York, in the State of New York, type-founder, have invented or produced a new set of printing types, for letter press printing, of a new & original design which I describe as follows, reference being had to the annexed printed

impression thereof. It is of the kind usually called Script & of the size usually called Double Great Primer, but it differs from every other script type in shape, size & proportion. As I intend to use this type as an addition to or in connection with my Double Great Primer Copper-plate Script heretofore Patented, I call this new type also for the purposes of this patent, Double Great Primer Copper-plate Script, & I claim the design of the said type as described and shown.

Witnesses: —

D. W. Bruce,

John Sullivan.
